UNITED STATES PATENT OFFICE.

CLINTON O. HARRINGTON, OF CHICAGO, ILLINOIS, ASSIGNOR TO ALDOBILT COMPANY,
OF CHICAGO, ILLINOIS, A CORPORATION OF ILLINOIS.

FOCUSING FINDER FOR LANTERNS.

Application filed June 2, 1921. Serial No. 474,543.

To all whom it may concern:

Be it known that I, CLINTON O. HARRINGTON, a citizen of the United States, and a resident of Chicago, in the county of Cook and State of Illinois, have invented certain new and useful Improvements in Focusing Finders for Lanterns, of which the following is a specification.

My present invention relates to means for focusing the source of light in lanterns adapted to project rays in a given direction, for instance in such lanterns as may be employed for railway signals, locomotive and other headlights, motion picture machines, etc.

Lanterns of the kind to which the present improvements are chiefly applicable include a lens or a reflector for directing the rays of light. The source of light is frequently an electric bulb in which the incandizable filament is "concentrated," that is, confined to comparatively small distances from a middle point. As is well understood, the most efficient projection is had when the maximum number of rays emanate from a small area or space at the focus of the lens or reflector, and therefore the aim in such cases usually is to have the concentrated lamp filament as close to such focus as conveniently may be. In railway signal practice it is often desirable to have the filament slightly away from the true focal point, but in any event the object always is to adjust the filament to that position in which it gives the best results.

Comparatively few of the concentrated filament lamps found in service have their respective filaments in such exact relation to the base or plug element of the lamp as to make the lamps interchangeable wherever they may be desired to be used and provide the desired result. It is therefore practically necessary to adjust each lamp individually in the lantern in which it is to be used.

The usual practice in railway signal work, when applying a new lamp to a lantern, is for one man to mount the mast or other structure supporting the lantern and manipulate the lamp adjustably while another man takes a position say a thousand feet down the track and observes the results of the various adjustments being made, this

work being done in the night time, the man down the track signaling with a lantern as to the results, and thus in the course of say 55 from one to three hours the lamp is focused sufficiently well for service.

In focusing the lamp provision must be made for moving it vertically, from side to side, and also in fore-and-aft directions. In 60 the common practice to which I have just referred provision is made for adjusting the lamp in these three ways. In my copending application filed March 22, 1921 as Serial No. 454,444 on a method of maintaining a 65 source of light in a desired position in a lantern, I have illustrated and described the lamp adjustment device illustrated herein in Figs. 1 and 2, according to which the filament of the lamp may be moved vertically, 70 horizontally, and in fore-and-aft directions, and in each instance without a modification of any other adjustment made. By reference to that application a more full illustration and description of the adjustment device may be had. In my said copending application I have also illustrated and described a finder device of the same general 75 character as the one herein disclosed and similarly applicable as an attachment to the 80 lamp adjustment device. According to that finder device one shaft of light falls directly upon a translucent chart through a small aperture, the beams passing through a chamber which excludes substantially all light but 85 those constituting the relatively small shaft. That device also includes a second chamber through which is cast by reflection a relatively long and narrow shaft of light which 90 falls upon a second translucent chart, the second light shaft emanating from the source at a materially large angle with respect to the beams constituting the direct shaft. According to that device the operator can make upon the one chart a reading 95 of the relative position of the source of light in vertical and lateral directions, and upon the second chart a reading of its relative position in fore-and-aft directions, and having made a record of the desired relative 100 position of the source in that particular installation he can replace the burned out lamp in a very brief space of time by simply inserting the new bulb and adjusting the source

in the several directions until the light shafts are indicated on the two charts in accordance with the record previously made.

One object of the present invention is to simplify construction without loss of advantage, reducing the size and weight of the finder and dispensing with one chart, thus enabling the operator to make his original record and his subsequent adjustments in view of a single chart, and obtain in a more easy and simple way the important and chief object and advantage of focusing or adjusting the lamp with greater ease, celerity, and, for the most part with greater accuracy than is possible according to the means and methods known prior to my inventions to which reference is made herein.

In the accompanying drawings, which form a part of this specification, Figure 1 shows in fragmentary form a railway signal lantern of approved construction, parts of the body wall being broken away to show the improved finder in side view upon the lamp-adjustment device; Fig. 2 is an enlarged rear view with the chart of the finder partially broken away to show more clearly how the finder as a whole is applied to the adjustment device shown in Fig. 1; Fig. 3 is a top plan of the finder device partly broken away to show construction and arrangement of otherwise concealed parts; Fig. 4 is a front end view of the finder and small fragments of the parts by which it is supported; and Fig. 5 is a sectional view on the line 5-5 of Fig. 3.

The signal lantern 10 is of well-known construction. It has a lens 11 in front and a vertically sliding door 12 permitting entrance from the rear. It is to be understood that the lantern is secured to a signal mast or other structure, and at a considerable elevation above the railroad track. Ordinarily there is a "spectacle" having several differently-colored glass screens or "roundels" operatively positioned in front of the lens whereby different signals may be given through the movement of the spectacle device, all as is well understood in the art. The mounting of the lamp above the ground and the use if desired of such a "spectacle" are not illustrated but are mentioned to show the application of these improvements to a railway signal lantern of that type. The desideratum is that the lamp within the lantern shall be kept burning with as little loss of time at replacement periods as possible, and with the lamp so positioned as to project light most efficiently.

The lamp-adjustment device includes an L-shaped carrying frame 15 secured by screws to the lantern bottom or base, and carries two lateral vertical rods 16 and a middle vertical threaded rod 17, each side rod having a stud 18 and the middle rod 19 having a stud 19 projecting above the ear

20 and the frame cross member 21 respectively. The vertically adjustable frame 22 is carried slidably by the vertical rods mentioned and is raised and lowered by the finger wheel 23. The frame 22 carries two fore-and-aft parallel rods 24 and the frame 25 is mounted slidably thereon. The frame 25 carries two laterally extending rods 26 and the frame 27 is mounted slidably on these. The lamp 28 having the concentrated filament 30 is mounted rigidly on the frame 27. By turning the screw 31 the frame 25 is moved in fore-and-aft directions carrying the frame 27 with it, and by turning the screw 32 the frame 27 is moved in lateral directions.

Inasmuch as the claims herein are directed to the finder device alone it is deemed sufficient to show in merely a general way how the various adjustments of the lamp are made, and to point out the essential fact that the filament 30 is adjustable in these three directions. For a full disclosure of the lamp-adjusting device reference may be had to my said copending application.

The finder device is shown as comprising top, bottom and side walls 35, 36, 37 and 38 respectively and an end wall 39. A mirror-supporting arm 40 extends laterally and then forwardly, and a pair of legs 41 extend downwardly, the walls, arm and legs being in my practice cast from aluminum. The bottom wall 36 carries a boss 43 bored to accommodate with an accurate but sliding fit the stud 19, and the legs 41 are accurately surfaced at 44 to press against the studs 18. The finder as a whole may thus be readily placed in operative position and removed therefrom.

The chart 45 consists of a translucent plate marked with vertical lines lettered A to I inclusive and horizontal lines numbered 1 to 9 inclusive after the well known manner employed in marking maps and other charts. The desired translucency may be obtained by sand-blasting a clear plate of glass on one side or in other ways well known and the chart may be of other materials such as celluloid. The markings on the chart may be by etching or by the application of paint or ink. The chart is held crosswise of the chamber, preferably at the end thereof, as by screws 46 and a clamping frame 47.

A fairly large hole 50 is bored through the end wall 39 and covering this hole is the plate 51 having screw holes large enough to provide considerable play with respect to the screws 52 whereby the plate may be moved adjustably for calibration and held in the desired position by screws or preferably by solder in addition to the screws. The plate 51 is provided with a relatively small hole or opening 53 therethrough, and in this connection it is pointed out that the

plate is positioned in the angle shown so that the form of the orifice 53 when viewed in the directions of the light shafts respectively passing through the hole and defined by it will be substantially the same.

The arm 40 carries a reflecting mirror 55 held in place by the ring-like plate 56 secured by screws 57. Within the chamber defined by the body walls there is a second 10 mirror 60 similarly held in place upon a carrier 61 mounted for rocking movement upon a vertical pin 62 rigidly secured in the top and bottom walls of the casing. The mirror carrying device 61 may therefore 15 rock on the pin 62, and means for holding it in a given angular relation comprise the screws 66 threaded in the casing wall, the advancing of one and the retracting of the other giving the desired modification in the 20 angle of the mirror 60. The mirror 60 is also preferably given a slight inclination from the vertical, which may be in one direction or the other and which is well shown in Fig. 5, as being such as to throw upward 25 the light shaft striking the mirror from the direction of the other mirror through hole 53.

The arrangement of the several parts in this preferred construction is well illustrated in Fig. 3, which is substantially true to scale, as are the other figures. The filament 30 is shown in Fig. 3 at what we will assume to be the focal point of the lens 11. It is thus clear that light rays emanating 30 from the filament 30 will reach and pass through the hole 53 from two directions, one being direct and shown by the dotted line 68 and the other being indirect or by reflection and shown by the lines 69 and 70, 35 both shafts falling on the chart 45 and being visible on the outer side thereof.

Owing to the difference in distance from the filament 30 to the orifice 53 and from the orifice 53 to the chart 45 the direct light 40 shaft will appear upon the chart as a spot which is proportionately larger than the filament itself, as substantially indicated at 75, Fig. 2, which indication also shows that this direct shaft falls upon the chart at its 45 middle point when the filament 30 is at the focal point of the lens, assuming that the instrument has been accurately positioned in the lantern. It is unimportant in practice just where, within the reasonable limits 50 of the chart, the light shaft indicated at 75, Fig. 2, may fall.

The spot or indication 76, Fig. 2, is that for the reflected shaft from the mirrors. It 55 is relatively smaller than the indication 75 because the distance along lines 69 and 70 to the orifice 53 compared with the distance from 53 to the mirror 60 and thence to chart 45 along line 71 is greater than the ratio of distance 30 to 53 to distance 53 to 45.

In practice the exact desired location of the filament with respect to the lens 11 is first determined in any approved way, as by the experimental test manner in the early part of this specification described. Thereupon the finder device is operatively positioned on the studs 18 and 19 and a reading made of the position of the spots of light as 75 and 76 on the chart 45. According to the requirements of a particular installation, or due to the fact that the lamp-holding-and-adjusting device may not have been positioned with precise accuracy, due to slight variations in machine work, these light spots 75 and 76 may not be even close 80 to the theoretical positions shown in Fig. 2 when the filament is properly adjusted with respect to the lens. This is immaterial. Whatever the position of the spots 75 and 76 respectively proves to be the adjuster 85 simply makes a record of them, either in a book which he may carry with him from time to time or, preferably, upon a tag or other card which he may leave within the lantern for future reference. Let us assume that after making the preliminary adjustment of the filament to determine its proper relative position the light beams are found to register at 75 and 76. The record 90 he would thereupon make from a reading 95 of the chart might be "Direct spot E-5; Reflected spot E-2." Since the spot 75 shows the relative location of the filament in both up-and-down and lateral directions of adjustments it is only necessary to consider the variation in position of the spot 76 caused by movements of the filament in fore-and-aft directions, and since the fore-and-aft movements of the filament cause the spot 76 to move in lateral directions on the 100 chart, it is really immaterial what the vertical position of the spot 76 may be. The record for spot 76 would be full enough if it merely recited "E." The tilt of the mirror 60 from the vertical determines how 110 far above or below this middle point of the chart the spot 76 will be, and such separation of the two spots is made merely for convenience in reading the chart. A further convenience may be had by making one of 115 the mirrors 55 or 60 of colored glass, as ruby or green, in which case the spot 76 will appear in the color of the colored reflector. The mirror 60 might be vertical, especially if a colored mirror be used, in 120 which event the two spots might coincide and still be perfectly distinct.

Subsequently, when it is desired to install a new lamp it is only necessary for the operator to remove the old lamp, apply the 125 new, add the finder, consulting the chart or record for that particular installation, and, by means of the adjustment features of the lamp-adjustment device (namely by turning the finger wheel 23 and the screws 130

31 and 32, as fully described in my said co-pending application) the spots of light as 76 and 75 may, in an exceedingly brief space of time, be brought to their desired 5 positions respectively, which establishes the filament exactly in the position previously found to be correct.

In this connection it is pointed out that the mirror 60 is adjustably mounted as by 10 means of the screws 66 so that the spot 76 may be suitably positioned as midway of the chart, when the instrument is calibrated prior to use. By means of this adjustment and that provided for the plate 51 the cali- 15 brator is able to overcome the effects of such differences in mechanical construction as almost of necessity exists in the manufacture of instruments of this general class or kind.

20 In the laboratory, according to my practice, each instrument is carefully calibrated with respect to a filament accurately positioned in standard relation to the studs 18 and 19 which determine the relative position 25 of the finder upon the lamp adjustment device. Having thus calibrated each instrument sent out from the shop, and the studs 18 and 19 of the lamp adjustment device being of uniform construction and ar- 30 rangement in each of the lamp-adjustment devices installed, the lamp maintainer, having provided himself with one of the finders, may use it in turn upon all of the installations of this kind which he may find on 35 his section of the line; and, further, should one of the finders be lost or broken another may be substituted without prejudice to the use with it of any of the records showing the desired adjustment in any installation.

40 While I have thus illustrated and de-scribed a highly advantageous construction and arrangement constituting an exceedingly simple, efficacious and readily-operable finder of the character described, I con- 45 template as being within the scope of the present invention various changes and modifications from what is herein specifically shown, as indicated by the appended claims.

I claim:

50 1. In a finder of the character described adapted to be positioned closely adjacent to a source of light to indicate relative positions of such source, the combination of a relatively small chart having markings associated therewith adapted to indicate relative 55 locations of relatively small light spots thereon, and means for projecting upon the chart two relatively small shafts of light from a given relatively small source, with said 60 shafts issuing from such source with a materially large angle between them, for defining two relatively small spots of light on the chart for indicating a relative position of the source of light.

65 2. A finder of the character described com-

prising in combination a chart, light-ob- structing means for maintaining the chart substantially free of light beams from a given relatively small source except in pre-determined relatively small shafts, and 70 means including a single passageway through said light-obstructing means for defining such relatively small shafts of light which fall upon the chart, the rays which constitute one shaft passing through said 75 passageway at a materially large angle with respect to the rays which constitute the other shaft and pass therethrough.

3. In a finder of the character described adapted to be positioned adjacent to a source of light, the combination of walls forming a chamber, a translucent chart between opposite chamber walls, there being a relatively small light aperture at one end portion of the chamber, the arrangement being such that rays of light may pass through said aperture as a relatively small shaft and fall directly upon said chart, and means including light-ray diverting means for throwing a second shaft of light from said source 80 through said aperture and upon said chart.

4. In a finder of the character described adapted to be positioned adjacent to a source of light to indicate relative positions of such source, the combination of a translucent chart, and means including light-reflecting means for projecting upon the chart two shafts of light from a given relatively small source with said shafts issuing from such source with a materially large angle between them for indicating a relative position of the source of light.

5. A finder of the character described comprising in combination a translucent chart, light-obstructing means for maintaining the chart substantially free of light beams from a given relatively small source except in pre-determined relatively small shafts, and means including light-ray diverting means and a single passageway through said light-obstructing means for defining such relatively small shafts of light which fall upon the chart, the rays which constitute one shaft passing through said passageway at a mate- 105 rially large angle with respect to the rays which constitute the other shaft and pass therethrough.

6. In a finder of the character described adapted to be positioned adjacent to a source of light, the combination of side walls and 110 an end wall forming a dark chamber, a translucent chart at one end of said chamber, the end wall at the other end of the chamber having a relatively small light aperture, the arrangement being such that 115 rays of light may pass through said aperture as a relatively small shaft and fall directly upon said chart, and means including two reflecting mirrors one thereof being within the chamber, for throwing upon said chart 120

- a second shaft of light the beams of which issue from the source at a materially large angle with respect to the beams constituting said other shaft.
7. A finder of the character described adapted to be positioned closely adjacent to a relatively small source of light and comprising walls forming a chamber, means at one end portion of the chamber for directing a relatively narrow shaft of light from such relatively small source of light through the chamber to show substantially as a small spot on a chart device, and a chart device at the opposite end of said chamber and constituting an attached part of the finder and having a normally fixed relation to said chamber walls and to said means for directing a shaft of light, said chart device having a field arranged to receive said shaft of light, the field of said chart device having markings defining a substantially large number of relatively small areas throughout the field, there being indicating characters associated with said markings whereby a record may be made in terms of said characters to indicate various relative positions of the source of light.
8. A finder adapted to be positioned adjacent to an adjustable source of light for determining the relative position of the source of light comprising a chart device having markings thereon for indicating movement of the source of light in horizontal, vertical and fore-and-aft directions, and means for projecting on the chart device a plurality of limited areas of light caused by beams issuing from the source in various directions.
9. The combination of a hollow lantern body having a doorway in one part thereof and a lens in another part thereof, a main support for a source of light within said body, and means carried by the main support within the lantern body and accessible through said doorway for holding in readily removable relation thereto an optical finder applicable through said doorway for determining relative positions of said source of light.
10. In a lantern, the combination of a lantern body, a source of light within said body, means for adjusting said source in various directions relative to the lantern body, means including a translucent chart closely adjacent to the lantern body and having a field divided into a substantially large number of relatively small areas adapted to receive rays from said source, and means for directing upon the chart a shaft of light from said source as a substantially-well defined spot for indicating a relative position of adjustment of the source of light.

CLINTON O. HARRINGTON.
